CLAIM

The ornamental design for a two-handle attachment for screw lid type jars, as shown and described.

DESCRIPTION

FIG. 1 is a left side elevational view of a two-handle attachment for screw lid type jars showing my new design, the opposite side being a mirror image thereof.

FIG. 2 is a front elevational view thereof.

FIG. 3 is a rear elevational view thereof.

FIG. 4 is a top plan view thereof.

FIG. 5 is a bottom plan view thereof.

FIG. 6 is a top perspective view thereof.

FIG. 7 is a left side environmental view showing my new design, screwed onto a screw lid type jar.

FIG. 8 is a front environmental view showing my new design, screwed onto a screw lid type jar.

FIG. 9 is a rear environmental view showing my new design, screwed onto a screw lid type jar.

FIG. 10 is a bottom plan environmental view showing my new design, screwed onto a screw lid type jar.

FIG. 11 is a top plan environmental view showing my new design, screwed onto a screw lid type jar; and,

FIG. 12 is a top perspective environmental view showing my new design, screwed onto a screw lid type jar.

In the drawings, the broken lines depict environment that forms no part of the claim.
